CLAIM

The ornamental design for a armless pull-out sofa bed, as shown and described.

DESCRIPTION

FIG. 1 is a front view of the armless pull-out sofa bed in a first position;

FIG. 2 is a front perspective view of the armless pull-out sofa bed in the first position;

FIG. 3 is a front perspective view of the armless pull-out sofa bed in a second position;

FIG. 4 is a front perspective view of the armless pull-out sofa bed in a third position;

FIG. 5 is a right side view of the armless pull-out sofa bed in the first position;

FIG. 6 is a left side view of the armless pull-out sofa bed in the first position;

FIG. 7 is a back perspective view of the armless pull-out sofa bed in the first position;

FIG. 8 is a back view of the armless pull-out sofa bed in the first position;

FIG. 9 is a front perspective view of the armless pull-out sofa bed in a fourth position;

FIG. 10 is a front perspective view of the armless pull-out sofa bed in a fifth position;

FIG. 11 is a front perspective view of the armless pull-out sofa bed in a sixth position;

FIG. 12 is a front perspective view of the armless pull-out sofa bed in a seventh position; and,

FIG. 13 is a front perspective view of the armless pull-out sofa bed in an eighth position.

The broken lines showing in FIGS. 1-13 are to show portions of the armless pull-out sofa bed, which form no part of the claimed design.

1 Claim, 13 Drawing Sheets
